ADJUSTABLE RING GROOVE CARBON
REMOVING TOOLCarl A. Stine, Van Nuys, Calif., assignor to Turco
Products, Inc., Los Angeles, Calif., a corpora-
tion of California

Application December 28, 1942, Serial No. 470,388

2 Claims. (Cl. 15—104.61)

This invention relates to devices for removing carbonaceous deposits from the ring grooves in pistons and the like.

It is among the objects of my invention to provide a device which embodies means for affording such adjustable resilient engagement of the cutter element with the deposited carbon as to obtain uniform action and prevent injury to the piston.

It is another object to provide a device which embodies means for efficiently guiding the cutter during its cutting movement about the ring groove.

It is another object to provide means for readily adjusting the device to pistons of various sizes and to provide a device which may be easily applied to and removed from a piston.

Another object is to provide a device of this character which is capable of being economically manufactured.

Still further advantages are to be derived from my invention and how those as well as the objects hereinabove particularly set forth are achieved will be best understood from the following detailed explanation of one of the adaptations of which my invention is susceptible, for which purpose I shall refer to the accompanying drawing, in which:

Fig. 1 is a top plan view with some parts shown in section;

Fig. 2 is a side view taken on line 2—2 of Fig. 1;

Fig. 3 is an enlarged end view of the cutter element;

Fig. 4 is an enlarged bottom plan view of one of the guide elements;

Fig. 5 is an enlarged fragmentary plan view showing one of the frame flanges;

Fig. 6 is an enlarged fragmentary plan view showing the other of the frame flanges; and

Fig. 7 is an enlarged fragmentary sectional view showing a variational form of cutter.

Referring now to the drawing, I show at 5 a circular frame comprised of segments 5a, 5b hingedly connected together by hinge 7. Each of the segments 5a, 5b has an end flange 8, 9, flange 8 having an elongated hole 9a to pass and permit lateral movement of a connecting bolt 10. Flange 9 is slotted at 9a to receive the opposite end of bolt 10, onto which end there is threaded a wing nut 10a. Surrounding bolt 10 and bearing at its opposite ends against the respective flanges 8, 9, I provide a coil spring 12, which spring moves the flange elements apart to expand the frame as the wing nut 10a is unscrewed. This means of connecting the adjacent ends of the

frame segments, together with the hinge 7, facilitates applying the device over the ends of a piston P and enables the device to operate on pistons of various sizes.

Circumferentially spaced and symmetrically arranged around the inner surface of the frame 5, and secured thereto as by rivets 15, I provide plates 16 which ride over the lands L of the piston, and each of the plates has a projection 17 which extends into a ring groove G of the piston, although projections 17 are not long enough to contact the bottom of the groove since those members serve merely as guides and are not intended as carbon cutting or scraping elements. As best shown in Fig. 4, projections 17 are preferably of square cross-section.

To the outside of frame segment 5a, diametrically opposite the bolt 10, I secure, as by welding, a tubular handle 20, there being a squared opening 21 through the wall of segment 5a concentric with the bore of tube 20 to slidably pass a cutter element 23.

Cutter 23 has an inner end of squared cross-section which bevels to a cutting edge 23a and a medial enlarged portion 23b of squared cross-section which slidably fits in opening 21. The inner, rounded end 23c of the cutter slidably fits the bore of tube 20. A retaining washer 24 is interposed between the rounded portion 23c of the cutter and the outer surface of frame segment 5a.

A cap 30 is threaded over the outer end of tube 20 and through a central opening in the cap I thread an adjusting screw 32 having a flattened head portion 32a and whose inner end has secured thereto a disc 34. A coil spring 35 is disposed longitudinally in the tube and bears at one end against the inner end of the cutter element 23 and bears at its other end against disc 34. Thus the cutter is resiliently mounted with its cutting edge 23a operating against the bottom of the piston groove G and it is possible to adjust this pressure of spring 35 by means of rotating the adjusting screw 32, a lock nut 35 being provided to lock the screw in adjusted position.

To apply the device over a piston, the lower end of bolt 10 is swung outwardly from the slot 9a—the elongated hole 8a in flange 8 permitting such lateral movement of the bolt—and the ring segments 5a, 5b may be swung apart about hinge 7 to apply them around a piston and to insert the cutting edge 23a of the cutter as well as the guide member 17 into the piston groove, after which the bolt 10 is swung back into the

slot 9a and the nut 10a tightened. After thus mounting the device, rotation of the frame with respect to the piston causes the cutting element to cut the carbon from the ring groove or at least to cut into it sufficiently to permit it to be attacked and finally removed by any one of the well known carbon removing chemical baths. It is usually undesirable for the cutter to cut into the metal of the piston and therefore I find it desirable to make the cutter of material not harder than the material of the piston.

In Fig. 7 I show a variational form of cutter 40 which comprises two cutting members 40a, 40b of different sizes disposed on opposite sides of a central rounded body portion 41. Here, while one of the cutting members is in use, the opposite cutting element is disposed within the bore of the tube 20. If it is desired to substitute the cutting member disposed within the tube for the other cutting member, it is necessary only to reverse them end for end by removing the cap 30 and spring 35, sliding the cutter element outwardly of the tube, reversing it and then reinserting it into the tube and re-applying the cap.

Within its broader scope as defined by the appended claims, the invention is susceptible of being carried out in other specific forms of device and I therefore do not wish to be limited to the specific details hereinabove described except to the extent that some of the claims may recite those specific details.

I claim:

1. In a device for removing carbon from a ring groove in a piston, a circular frame formed to

encircle the piston in position over the groove, plates carried by the frame in position to frictionally engage the lands of the piston, groove-following guides carried by the plates in position 5 to project into the groove, a cutter element carried by the frame in position to project into the groove, said frame being comprised of a pair of semi-circular segments hingedly connected together at one end, compression spring means 10 interposed between the other ends of the segments to normally urge them apart and adjusting means for moving the last-named ends of the segments towards each other against the compression of the spring whereby to adjust the frictional engagement of the plates with the lands of the piston.

2. A device for removing carbon from a ring groove in a piston comprising a frame formed to encircle the piston, said frame consisting of two 20 curved segments hingedly connected together at one end, an adjusting bolt extending between the other ends of the segments, a coil spring disposed around the bolt and resiliently spacing the last-named ends of the segments apart, radially 25 inwardly disposed guide projections carried by the frame for guiding movement along the groove, each of the guide projections having a portion slidably engageable against the outer surface of the lands of the piston, and a cutter 30 element resiliently carried by the frame and projecting radially inwardly therefrom to cuttingly engage carbon deposited in the groove upon rotation of the frame relative to the piston.
